(57) **CLAIM**

The ornamental design for a two-sided tab as shown and described.

DESCRIPTION

FIG. 1 is a perspective view of a first embodiment of a tab showing our new design;

FIG. 2 is a perspective view of a second embodiment of a two-sided tab showing our new design;

FIG. 3 is a perspective view of a third embodiment of a two-sided tab showing our new design;

FIG. 4 is a perspective view of a fourth embodiment of a two-sided tab showing our new design;

FIG. 5 is a first side view of the embodiment of FIG. 11 of the two-sided tab showing our new design;

FIG. 6 is a second side view of the embodiment of FIG. 11 of the two-sided tab showing our new design;

FIG. 7 is a first side view of the embodiment of FIG. 2 showing our new design;

FIG. 8 is a second side view of the embodiment of FIG. 2 showing our new design;

FIG. 9 is a first side view of the embodiment of FIG. 3 showing our new design;

FIG. 10 is a second side view of the embodiment of FIG. 3 showing our new design;

FIG. 11 is a first side view of the embodiment of FIG. 4 showing our new design; and,

FIG. 12 is a second side view of the embodiment of FIG. 4 showing our new design.

The broken lines in the figures are included for the purpose of illustrating portions of a two-sided-tab and form no part of the claimed design.

1 Claim, 6 Drawing Sheets
